UNITED STATES PATENT OFFICE.

EDWARD WALDER, OF LA GRANGE, ILLINOIS.

SANITARY TOILET-SEAT.

1,160,963.

Specification of Letters Patent.

Patented Nov. 16, 1915.

Application filed November 20, 1914. Serial No. 873,109.

To all whom it may concern:

Be it known that I, EDWARD WALDER, a citizen of the United States, residing at La Grange, in the county of Cook and State of Illinois, have invented certain new and useful Improvements in Sanitary Toilet-Seats, of which the following is a specification.

This invention relates to improvements in sanitary toilet seats, and has reference more particularly to that class of such devices wherein the upper surface of the seat proper, when not in use, is subjected to the action of a disinfectant and deodorizing material for sanitary purposes.

15 The main object of the invention is to provide an improved toilet seat of this type, and one wherein the seat proper may be most effectively and thoroughly disinfected at all times when not in use.

20 Another object of the invention is to provide a toilet seat of the character specified which shall enable the bowl and seat proper to be easily and thoroughly cleaned, when required, especially in those parts that are 25 more or less inaccessible for cleaning purposes in the common or ordinary toilet seat.

Another object of the invention is to provide a construction readily facilitating the application and renewal of the disinfecting 30 agent when required.

Other minor objects and benefits of the invention will be apparent from the following description, taken in connection with the accompanying drawing wherein I have illustrated one approved mechanical embodiment 35 of the invention and in which—

Figure 1 is a side elevation of my improved toilet seat, the seat proper being shown by full lines in service position and by dotted lines in its normal elevated position; Fig. 2 is a top plan view of the same, partly broken out and in horizontal section; Fig. 3 is a front elevation.

Referring to the drawings, 5 designates the bowl which may be in the usual form. Extending through apertures in the rear upper extension 5' of the bowl are the threaded vertical ends 6 of a pair of bent rods 7, secured strongly in place by nuts 8 and 9. The rods 7 extend laterally and forwardly beneath the upper rim of the bowl, and constitute supports for the side arms 10 of a bail-shaped frame piece 11, said arms being hinged to the rods 7 by pivot bolts or

studs 12. Mounted on the forward end of 55 the frame member 11 is the seat proper 13, which, in accordance with the present invention, is made of a generally shallow U-form, so as to cover something less than the forward half of the upper rim of the bowl. 60

Threaded onto the upper ends 6 of the rods 7, and thereby locking the nuts 8 in place, are a pair of tubular posts 14, on which is mounted a seat casing 15 that preferably, and as herein shown, has an outline 65 shape and size substantially following the shape and size of the seat block 13. This casing, as shown, has top, bottom, side and rear walls and an open front, its top and bottom walls being suitably apertured to receive the posts 14. The casing is supported on its underside by collars 16 adjustably mounted on the posts 14 by set-screws 17, and the upper ends of the posts 14 are threaded to receive nuts 18, by which the 70 casing is securely clamped and confined on the post.

Within the rear portion of the casing 15 is located a thin sheet metal box 19 having a perforated front wall 20 and adapted to contain absorbent cotton or similar material 80 thoroughly impregnated with any suitable material having one or all of the qualities of disinfecting, antiseptic and deodorizing substances, this box being normally confined in 85 place between the rear wall of the main housing 15 and the posts 14.

The arms 10 of the seat frame 11 are extended rearwardly of their hinges 12 and, at their rear ends carry, or are formed with, 90 counter-weights 21 that normally act to maintain the frame and seat piece in the elevated position shown by dotted lines in Fig. 1 wherein it will be noted that the seat piece 13 has entered the open front of the 95 casing 15 and is housed within the latter where its upper surface is thoroughly subjected to the action of the fumes emitted by the disinfecting material through the perforated front wall of its container. When the 100 seat is to be used it is simply drawn down to the horizontal position shown by full lines in the several figures, and, when released from the weight of the occupant, the weights 21 automatically restore it to elevated position.

I am aware that it has heretofore been proposed to provide a vertical support in

rear of a hinged toilet seat, and to secure a disinfectant pad to the front surface of said support, said pad acting upon the upper surface of the seat maintained in elevated position by spring hinges. In such a construction, however, the seat receives only a small per cent. of the disinfecting action and capacity of the pad, since the fumes are not confined and directed upon the surface of the seat, but are more or less scattered and dispersed in other directions, especially where there may be more or less of a current of air passing between the seat and the pad. It will be noted that in my improved device the seat is completely housed within and practically fills the open front of the disinfectant casing, so that drafts are shut off, and the upper surface of the seat is necessarily bathed in practically all the fumes that escape from the disinfectant.

It will further be noted that the partial or skeleton form of seat piece herein disclosed, in combination with the elevated disinfectant support and housing leaves the rear portion of the bowl entirely free and open and capable of being easily and thoroughly cleaned. When it is necessary to renew the disinfectant, all that is required is to remove the nuts 18, draw the casing 15 off the posts 14, withdraw the disinfectant box 19 through the open front of the housing, recharge and replace the same, and remount the casing on the posts. The casing 15 may be made of any suitable or desired material, but is readily capable of being made in porcelain or any other ornamental material harmonizing with the material of the bowl. When the seat is in use, the posts 14 and the front edge of the casing 15 are ample to protect the clothes of the user from direct contact with the perforated front of the disinfectant box, so that there is no danger of soiling or injuring the clothes of users of the device.

It will be manifest to those skilled in this art that the structure described may be modified in many details without departing from the principle of the invention or lessening the practical utility thereof. Hence, the invention is not limited to the precise form, structure and arrangement of coöperating parts shown and described, except to the extent indicated within the purview of the appended claims.

I claim:

1. A sanitary toilet seat comprising, in combination, a bowl, a hinged seat, a casing having top, bottom, side and rear walls and a permanently open front mounted above the rear portion of said bowl, and a pad of a size to completely cover said seat charged with disinfectant material filling the rear portion of said casing; said seat, when swung to upright position, entering the open front of said casing and being housed therein with its entire upper surface

exposed face to face to the outer surface of said pad and directly receiving the fumes from the latter.

2. A sanitary toilet seat comprising, in combination a casing having top, bottom, side and rear walls and a permanently open front mounted above the rear portion of said bowl, a box having a perforated front wall occupying the rear portion of said casing, and a pad of a size to completely cover said seat charged with disinfectant material in said box; said seat, when swung to upright position, entering the open front of said casing and being housed therein with its entire upper surface directly exposed to and receiving the fumes from said pad.

3. A sanitary toilet seat comprising, in combination, a bowl, an upright support in rear of said bowl, a casing mounted on said support, the latter extending across the open front portion of said casing, a pad charged with disinfectant material housed in the rear portion of said casing behind said support, and a hinged seat block adapted to swing between an operative position on the forward portion of said bowl and an idle position within the front portion of said casing where it is directly exposed to the fumes from said pad.

4. A sanitary toilet seat comprising, in combination, a bowl, a pair of posts mounted on the rear of said bowl, a casing having an open front and apertured top and bottom walls whereby it is slidably mounted on said posts, means for supporting said casing on said posts, a disinfectant material in the rear portion of said casing, and a hinged seat-block adapted to swing between an operative position on the forward portion of said bowl and an idle position within the front portion of said casing.

5. A sanitary toilet seat comprising, in combination, a bowl, a pair of posts mounted on the rear of said bowl and having threaded upper ends, a casing having an open front and apertured top and bottom walls whereby it is slidably mounted on said posts, vertically adjustable collars on said posts for supporting said casing on the latter, nuts on the upper ends of said posts for confining said casing in place, a disinfectant material in the rear portion of said casing, and a hinged seat-block adapted to swing between an operative position on the forward portion of said bowl and an idle position within the front portion of said casing.

6. A sanitary toilet seat comprising, in combination, a bowl, a pair of supporting rods extending alongside said bowl and having upwardly bent threaded rear end portions passed through apertures in the rear portion of the rim of said bowl, nuts confining said threaded end portions of the rods in place, a pair of counterweighted arms

pivoted to said supporting rods, a seat-block mounted on the forward ends of said arms and covering only the front portion of the rim of said bowl, a pair of tubular posts 5 mounted on the threaded upper ends of said supporting rods, a casing mounted on said posts and having an open front adapted to receive and house said seat-block when swung to upright position, and a body of disinfectant material in the rear portion of 10 said casing.

EDWARD WALDER.
